UNITED STATES PATENT OFFICE

FREDERICK C. HEINEN AND WILLIAM W. DARROW, OF CHICAGO, ILLINOIS, ASSIGNEES
TO CAMEL COMPANY, OF CHICAGO, ILLINOIS, A CORPORATION OF ILLINOIS

DOOR

Application filed August 6, 1925. Serial No. 48,460.

The present invention relates to doors.

More particularly the present invention relates to sliding doors such as are used on railway box cars.

5 An object of the present invention is to provide a door which may be conveniently assembled from standard parts and which is well adapted to withstand the stresses encountered in service.

10 A further object is to provide a ribbed door which is light in weight and efficient in service.

15 A further object is to provide a railway car door of ribbed construction which will present a water shedding outer surface and a substantially flat inner surface.

Further objects will appear as the description proceeds.

Referring to the drawings—

20 Figure 1 is a fragmentary view of the side of a railway box car having a door applied thereto embodying the principles of the present invention;

25 Figure 2 is a sectional view taken along the plane indicated by the arrows 2—2 of Figure 1;

Figure 3 is a sectional view taken along the plane indicated by the arrows 3—3 of Figure 1;

30 Figure 4 is a fragmentary view showing a detail of construction;

Figure 5 shows another detail of construction;

35 Figure 6 is a sectional view taken along the plane indicated by the arrows 6—6 of Figure 1; and

40 Figures 7 and 8 are fragmentary views in perspective illustrating the ribbed construction of a door embodying the principles of the present invention.

The side wall of a railway box car is indicated by the numeral 10. Said side wall is provided with a structural steel member 11, which provides a track for supporting the 45 sliding door 12. Referring to Figure 6, it will be noted that in the illustrated embodiment of the present invention the member 11 comprises a T-shaped structure of which the leg portion 13 occupies a substantially horizontal position. Carried by the door 12 are

the brackets 14—14, which are provided with the rollers 15—15 adapted to ride upon the upper surface of the portion 13 of the member 11. Said brackets 14—14 are also provided with the rollers 16—16 adapted to engage the under side of the portion 13 of the member 11 for preventing the door 12 from being lifted out of proper cooperative relationship with the doorway of the car. The door 12 is bounded at its upper edge by the Z-bar member 17, the upper flange of which cooperates with the frame of the car and with the track member 11 to guide the upper portion of the door 12. The lower edge of the door 12 is bounded by the Z-bar member 18, which is adapted to cooperate with the brackets 19—19 mounted upon the frame of the car for guiding the lower portion of the door 12. The two side edges of the door 12 are bounded by the h-bars 20 and 21. Said h-bars 20 and 21 comprise structures which may be described as channel members having an extra flange mounted in proximity to one of the flanges of said channel member. Said h-bars are articles of commerce, are readily purchasable in the open market, and therefore require no detailed explanation. The channel portions of the h-bars 20 and 21 have flanges 22—22 adapted to receive the ribs or corrugations of sheet metal plates which will be referred to hereinafter. The flange 23 of the h-bar 20 is adapted to cooperate with the angle member 24 located upon the door jamb 25 of the car to act as a piloting member. The h-bar 21 has its flange 26 turned backwardly to cooperate with the weather strip member 27, which weather strip member 27 is located in a vertical position adjacent to that portion of the doorway opposite to the jamb 25.

45 The structural steel members 17, 18, 20 and 21 form a rectangular frame, which frame is filled in by means of structural steel members which are formed with ribs or corrugations for strengthening purposes. Referring to Figures 6 and 7, a steel plate 28 is provided having an outwardly struck rib portion 29' adapted to underlie the outer flange of the Z-bar 17. The box provided by the web of the structural steel member 17 and the outstruck 50

rib 29' of the steel plate 28 is closed on the rear side of the door by means of the steel plate 30. Rivets 31—31 are provided for holding the Z-bar 17, plate 28 and plate 30 together, certain of said rivets 31 being also utilized to hold the brackets 14—14 in place. In order to prevent crushing of the material at the rivets 31—31, filler blocks 32 are provided between plate 30 and the rib 29. The sheet metal plate 28 is ribbed, as indicated by the numeral 33, close to its lower extremity, a depending portion 34 being provided below the ribbed portion 33. Arranged in echelon with the sheet metal plate 28 is the sheet metal plate 29, the upper portion of which underlies the rib 33 of the plate 28. The upper extremity of plate 29 is riveted to the plate 28 at a region spaced slightly above the rib 33, the plate 28 having a slight offset portion 35 to provide a recess for the upper portion of the plate 29, whereby to avoid an upwardly presented shoulder at the upper edge of plate 29. The rivets 31—31 connect the rib 33 with the plate 29 and structural steel members 20 and 21, filler blocks 32 being provided for strengthening purposes.

The plate 29 is ribbed adjacent to its lower extremity in a manner similar to that described above in connection with the plate 28, the ribbed portion of the plate 29 being indicated by the numeral 36. Said plate 29 is offset slightly, as indicated by the numeral 35, to receive the upper extremity of another plate located in rear of the rib 36 of plate 29.

The number of ribbed plates may be chosen as desired, the lowermost plate having an outwardly presented rib 37, which has a downwardly extending portion lying outwardly of the vertically presented flange of the Z-bar 18 at the bottom of the door. A plate 38 will underlie the rib 37, said plate 38, rib 37, Z-bar 18 and h-bars 20 and 21 being connected together by rivets 39, which rivets 39 are provided with the filler blocks 32 to prevent crushing.

The extremities of the ribs above referred to are located between the flanges 22—22 of the h-bars 20 and 21. By reason of the protection provided by said ribs and by the h-bars 20 and 21, together with the rivets and filler blocks used in connecting said parts together, a very sturdy construction is provided without requiring the use of heavy gauge material. It will be noted that the steel plates 28, 29 and 38 are so arranged that said plates overlap the neighboring plates immediately underlying same, so that water is shed outwardly of the door. By reason of the fact that each of said plates referred to is set into a recess in the rear of the plate which it underlies, no upwardly presented shoulders are presented for collecting grain or other finely divided lading.

The present invention provides a water-proof door of exceedingly sturdy construc-

tion, with a minimum of weight and at a minimum of cost. The above described embodiment of the present invention adapts itself for various modifications which may be preferred by the car owners. According to the structure shown in Figure 4, the h-bar 20 takes the form of the H-bar 41, which may provide an effective seal when the door is moved to closed position. According to Figure 5, a modification is provided in which the flange 26 of the h-bar 21 is bent in the form of a V to cooperate with a channel-shaped weather strip 42.

The present invention provides a water-proof door of sturdy construction which is light in weight and cheap to manufacture and which adapts itself to a number of modifications. It is intended to cover all such modifications that fall within the scope of the appended claims.

What is claimed is:

1. A railway car door comprising a rectangular frame made up of structural steel members, said structural steel members at opposite vertical sides of said frame comprising integral h-bars including channel portions and metal plates having horizontal ribs mounted in said frame with the ribs of said plates located within said channel portions, said h-bars having portions shaped to provide a rear edge angle at the rear edge of said door and a piloting member at the front edge of said door, said structural steel member at the bottom of said frame comprising an angular member having an outwardly presented vertical flat face, the lowermost of said plates having its lower edge portion disposed outwardly of said angular member and within said channel portions.

2. A railway car door comprising a rectangular frame made up of structural steel members, said structural steel members at opposite vertical sides of said frame comprising integral h-bars including channels portions and metal plates having horizontal ribs mounted in said frame with the ribs of said plates located within said channel portions, said metal plates being arranged in echelon and being overlapped to shed water outwardly of said door, said structural steel member at the bottom of said frame comprising an angular member having an outwardly presented vertical flat face, the lowermost of said plates having its lower edge portion disposed outwardly of said angular member and within said channel portions.

3. A railway car door having a substantially flat inner surface comprising a rectangular frame made up of structural steel members, said structural steel members at opposite vertical sides of said frame comprising integral h-bars including channel portions and metal plates having horizontal ribs mounted in said frame with the ribs of said plates located within said channel portions,

- said metal plates being arranged in echelon and being overlapped to shed water outwardly of said door, said plates being located to close the pockets formed by the inwardly presented portions of the ribbed portion of adjacent plates, said structural steel member at the bottom of said frame comprising an angular member having an outwardly presented vertical flat face, the lowermost of said plates having its lower edge portion disposed outwardly of said angular member and within said channel portions. 5
4. A railway car door comprising structural steel members providing a rectangular frame, said steel members at opposite vertical sides of said frame including channel portions, steel plates located within said frame and secured to said structural steel members, certain of said steel plates having horizontal ribs, said steel plates being arranged in echelon with an outwardly presented metal plate having its lower extremity in overlapping relationship with the adjacent metal plate at a lower level, whereby to shed water outwardly 15 of said door, the flat portions of certain of said plates being mounted in covering relationship with the inwardly presented face of the ribbed portion of an adjacent face, said structural steel member at the bottom of said frame comprising an angular member having an outwardly presented vertical flat face, the lowermost of said plates having its lower edge portion disposed outwardly of said angular member and within 20 said channel portions. 25
5. A railway car door comprising structural steel members providing a rectangular frame, said steel members at opposite vertical sides of said frame including channel portions, steel plates located within said frame and secured to said structural steel members, certain of said steel plates having horizontal ribs, said steel plates being arranged in echelon with an outwardly presented metal plate having its lower extremity in overlapping relationship with the adjacent metal plate at a lower level, whereby to shed water outwardly 30 of said door, the flat portions of certain of said plates being mounted in covering relationship with the inwardly presented face of the ribbed portion of an adjacent face, said structural steel member at the bottom of said frame comprising an angular member having an outwardly presented vertical flat face, the lowermost of said plates having its lower edge portion disposed outwardly of said angular member and within 35 said channel portions. 35
6. A railway car door comprising a rectangular frame made up of structural steel members, said structural steel members at opposite vertical sides of said frame comprising h-bars including channel portions and metal plates having horizontal ribs mounted in said frame with said ribs of said plates located within said channel portions, the outwardly extending portions of said h-bars being shaped to provide a rear edge angle and a piloting member at the rear and front edges of said door respectively, and filler members disposed within said channel members and said ribs to protect said ribs, the lowermost of said plates having its lower edge portion disposed outwardly of the steel member at the bottom of said frame and disposed within said channel portions. 40
- Signed at Chicago, Illinois this day of Aug. 3, 1925. 45
- FREDERICK C. HEINEN.
WILLIAM W. DARROW. 50
7. A railway car door comprising a rectangular frame made up of structural steel members, said structural steel members at opposite vertical sides of said frame including channel portions, having horizontal ribs, metal plates mounted in said frame with the ribs of said plates located within said channelled portions, and filler members disposed within said channelled portions and said ribs, said metal plates being arranged in echelon and being overlapped to shed water outwardly of said door, said structural steel member at the bottom of said frame comprising an angular member having an outwardly presented vertical flat face, the lowermost of said plates having its lower edge portion disposed outwardly of said angular member and within 55 said channelled portions. 55
8. A railway car door comprising a rectangular frame made up of structural steel members, said structural steel members at opposite vertical sides of said frame comprising h-bars including channel portions and metal plates having horizontal ribs mounted in said frame with said ribs of said plates located within said channel portions, the outwardly extending portions of said h-bars being shaped to provide a rear edge angle and a piloting member at the rear and front edges of said door respectively, and filler members disposed within said channel members and said ribs to protect said ribs, the lowermost of said plates having its lower edge portion disposed outwardly of the steel member at the bottom of said frame and disposed within 60 said channel portions. 60
